United States Patent

Des. 242,074
Patented Oct. 26, 1976

242,074

GUITAR OR SIMILAR ARTICLE

Michael Kasha, Tallahassee, Fla., and Stanley E. Rendell and Richard L. Schneider, Kalamazoo, Mich., assignors to Norlin Music, Inc., Lincolnwood, Ill.

Filed May 12, 1975, Ser. No. 576,327

Term of patent 14 years

Int. Cl. D17—03

U.S. Cl. D56—1 A

FIG. 1 is a front elevational view of a guitar or similar article showing our new design;

FIG. 2 is a side elevational view of the left side thereof;

FIG. 3 is a side elevational view of the right side thereof;

FIG. 4 is a back elevational view thereof;

FIG. 5 is a view of the top end thereof; and

FIG. 6 is a view of the bottom end thereof.

We claim:

The ornamental design for a guitar or similar article, substantially as shown and described.
